David Newmeyer - New York, N.Y. - a Trade mark.

PATENTED

NOV. 9 1889

United States Patent Office.

DAVID NEUMANN, OF NEW YORK, N. Y.

Design No. 3,747, dated November 9, 1869.

DESIGN FOR A TRADE-MARK.

The Schedule referred to in these Letters Patent and making part of the same.

To all whom it may concern:

Be it known that I, DAVID NEUMANN, of New York, in the county and State of New York, have invented and produced a new and original Design for Locks for Satchels, Carpet-Bags, and similar articles, as a trade-mark, of which the following is a specification.

My design consists of a "female head," representing the "goddess of Liberty" in or near the centre of the face-plate of the lock-casing, said figure-head being connected with the bolt in the inside of the lock in such a manner as to open the lock by moving this figure-head upward.

The face-plate of the said lock-case is covered with a number of "stars," which are either engraved, stamped, or embossed on the same, and surround the figure-head representing the goddess of Liberty.

These locks being always sold attached to the frames for satchels, carpet-bags, and similar articles, I shall call the same the "liberty-frame."

I claim, as my invention—

The design for a trade-mark, as described and shown.

DAVID NEUMANN.
